(57) **CLAIM**

We claim the ornamental design for a holder, as shown and described.

DESCRIPTION

FIG. 1 is a front/right/top perspective view of a holder (a front/left/top perspective view would be a mirror image thereof);

FIG. 2 is a rear/left/top perspective view thereof (a rear/right/top perspective view being a mirror image thereof);

FIG. 3 is a front elevational view thereof;

FIG. 4 is a bottom plan view thereof;

FIG. 5 is a rear elevational view thereof;

FIG. 6 is a left side elevational view thereof;

FIG. 7 is a right side elevational view thereof; and,

FIG. 8 is a top plan view thereof.

The broken lines adjacent contour lines represent the bounds of the claimed design and form no part of the claimed design. All other broken lines are directed to portions of the holder that form no part of the claimed design.
